CLAIM

I claim the ornamental design for a gun chamber cartridge indicator, as shown and described.

DESCRIPTION

FIG. 1 is an environmental perspective view of the gun chamber cartridge indicator inserted into the barrel of a handgun, the handgun forming no part of the claimed design;

FIG. 2 is a first perspective view of the first embodiment of a gun chamber cartridge indicator, showing my newdesign; FIG. 3 is a second perspective view thereof;

FIG. 4 is a top view thereof;

FIG. 5 is a right side view thereof;

FIG. 6 is a left side view thereof;

FIG. 7 is a bottom view thereof;

FIG. 8 is a first end view thereof;

FIG. 9 is a second end view thereof;

FIG. 10 is a first perspective view of the second embodiment of a gun chamber cartridge indicator, showing my new design;

FIG. 11 is a second perspective view thereof;

FIG. 12 is a top view thereof;

FIG. 13 is a right side view thereof;

FIG. 14 is a left side view thereof;

FIG. 15 is a bottom view thereof;

FIG. 16 is a first end view thereof; and,

FIG. 17 is a second end view thereof.

The broken lines in FIG. 1 disclose an unclaimed firearm; the broken lines in the second embodiment shown in FIGS. 10-17 disclose unclaimed lateral scoring. The broken lines form no part of the claimed design.
